UNITED STATES PATENT OFFICE

2,573,514

REVERSIBLE ELECTRIC SWITCH

William W. Turner, Drexel Hill, Pa., assignor to
General Electric Company, a corporation of
New York

Application December 21, 1949, Serial No. 134,263

4 Claims. (Cl. 200—159)

1

The invention relates to electric switches, particularly encased auxiliary switches suitable for gang mounting on circuit breaker operating mechanism or the like to perform various auxiliary controlling or signalling functions. In such service it may be necessary that some of the auxiliary switch units be normally closed and others be normally open in order to perform the required control or signal function.

One object of the present invention is to provide an improved simplified form of encased reversible switch unit having a biased operating member for biasing the switch contacts either normally closed or normally open merely by reversing these parts in the case with respect to the biased operating member.

Another object is to provide an improved reversible switch unit having an open front mounting case provided with a biased push button mounted in the case to project from one side thereof and provided with interlocking means for removably and reversely mounting the stationary and movable contact parts inside the case in reverse operating relation with the biased push button to normally engage or disengage the switch contacts and with the cases of a plurality of the switch units adapted for gang mounting in alignment to close the side of each adjacent case so as to hold the removable parts in proper operating relation and maintain all of the biased push buttons in alignment to be operated by a common movable finger irrespective of whether the individual switch units are normally biased closed or open.

Other objects and advantages of the invention will appear in the following description of the accompanying drawing in which Fig. 1 is a front view of an encased reversible switch unit embodying the improvements of the present invention with the removable contact parts assembled in the open front case to be normally biased open; Fig. 2 is a similar view of the reversible switch unit of Fig. 1 with the push button in section and showing the contacts closed when the push button is moved against its bias; Fig. 3 is a top view of a multi-stage switch showing the gang mounting of a plurality of switch units to close the case of each adjacent unit to hold the parts in operating relation with the contacts either normally biased closed or open and with the end unit shown in section in order more clearly to reveal the details of construction of the biased push button operating member and the reversibly mounted terminals; and Fig. 4 is a front view of the improved encased switch unit with the removably mounted parts assembled in the case so that the switch contacts are normally biased closed.

As shown in Fig. 1, the improved reversible switch unit indicated generally by the reference character 10 is provided with an open front case 11, preferably molded of suitable insulating material to removably and reversely mount in cooper-

2

ating relation therein the stationary contact member 12, the movable contact member 13 and the push button operating member 14 when the cover 15 is secured in place. As more clearly shown in Fig. 2 and Fig. 4, the stationary contact member 12 has a lateral contact facing 12a at its lower end and is right-angled at its upper end into L shape to form an integral terminal for mounting one of the terminal binding screws 16 outside the case and is provided with oppositely projecting stakes 17 for sidewise removable nesting engagement with corresponding depressions 18 formed as shown in Fig. 3 at the bottom of each of the spaced-apart slots 19 and 20 through the upper end of the case 11. The spaced apart slots 21 are provided for receiving the binding screw 16. Thus, the stationary contact member 12 may be removably and reversely mounted in either of the slots 19 or 20 with screw 16 in the corresponding slot 21 formed in case 11 depending upon whether the switch is to be normally open or normally closed.

The movable contact member 13 is substantially U-shaped with the contact facing 13a carried laterally on the longer leg thereof and with the bend of the U, 13b, adapted to be reversely mounted on the pivot pin 21 with both legs of the U extending through the square aperture 22 formed in the operating member 14. The pin 21 may be molded in the case 11 adjacent the concave bottom wall 23 or may be removably mounted therein so as to rotatably mount the bend 13b in the U-shaped movable contact 13 therebetween. The right-angled upper end 13c of the U-shaped movable contact member 13 is connected by the flexible conductor 24 with an L-shaped terminal 26 carrying binding screw 16 that is substantially a duplicate of the stationary contact member 12 only without the contact facing and consequently is provided with duplicate projecting stakes 17 on the opposite sides thereof for interlocking engagement with either the recess formed in the bottom of the slot 20 or the recess at the bottom of slot 19. By means of this improved reversible construction all parts of the switch may be reversely mounted in case 11 as shown in Fig. 4 in order to produce a normally closed switch whenever desired.

As more clearly shown in Fig. 3, the push button operating member 14 is provided with oppositely offset rectangular ends 30 and 31 with the central rectangular aperture 22 midway therebetween for receiving both legs of the reversible U-shaped movable contact member 13 into operating relation therewith. The end 30 of the operating member 14 slides through a rectangular aperture formed in the side wall of the case 11 as indicated by the dotted lines in Fig. 2 and the oppositely offset end 31 is removably and slidably mounted in an open rectangular slot 33 formed in the opposite side wall of the case 11 so that the projecting end 31 can serve as a push button. The bias-

ing spring 35 has one end seated around the guide pin 36 formed on the operating member 14 and the other end seated inside a recess 37 formed in the side of the case 11. In this way the operating member 14 is normally biased to operate the movable contact member 13 out of engagement with the stationary contact member 12 when the switch parts are assembled as shown in Figs. 1 and 2. When force is applied to the push button end 31 for operating member 14 against its bias to engage the switch contacts 12 and 13 as shown in Fig. 2, the resilience of the U-shaped movable contact 13 serves to maintain a wiping contact pressure therebetween.

In case it is desired that the switch be normally closed, all that is necessary is to reverse the mounting of the stationary contact member 12 and the terminal member 26 in the slots 19, 20 and 21 as shown in Fig. 4 while at the same time reversely pivoting the U-shaped contact member 13 on the pivot pin 21 with the member extending through the aperture 22 in the biased operating member 14. In this way without the use of any tools the switch is readily converted into the normally closed type since the biasing spring 35 now will tend normally to maintain the contacts 12 and 13 in circuit closing engagement so that these contacts will be disengaged when the operating member 14 is operated against its bias. To effect such conversion, the front cover 15 must be removed whereupon all the operating parts can be easily moved laterally out of their operating positions in the case 11. The U-shaped member 13 can then easily be reversely inserted through the aperture 22 in member 14 into pivotal engagement with the pin 21 and the parts 12 and 26 reversely slid in interlocking engagement in the slots 19 and 20 and the cover 15 replaced to hold all parts in reverse operating relation in case 11 with the terminal connection screws 16 readily accessible outside the case.

In the multi-stage auxiliary switch construction shown in Fig. 3, a plurality of duplicate switch units 10 having open front cases 11a, 11b, 11c stacked in alignment so that the back of one closes the front of the adjacent case with the front cover 15 closing the face of the end case are gang mounted by means of the through bolts 40 and 41 which may be secured to a frame or bracket 42 of a circuit breaker operating mechanism or the like. In this way the push button ends 31 of all units are aligned to be jointly operated by a common operating member or finger 43 preferably formed of resilient material and mounted on a pin 44 carried on an arm 45 extending from the shaft 46 so as to be moved to the position shown in Fig. 1 when the circuit breaker mechanism is closed and to the position shown in Fig. 2 when the circuit breaker mechanism is open. Thus, all of the operating members 14 of the switch units are jointly operated against their bias by the common operating finger 43 and each unit may be either normally closed or open.

What I claim as new and desire to secure by Letters Patent of the United States is:

1. An electric switch having in combination, a stationary contact member, a movable contact member of U-shape, and a case having a biased operating member mounted therein and provided with means for reversely mounting the stationary contact member in two spaced-apart positions therein and means including a pivot pin engageable reversely with the bend of the U-shaped contact member for reversely pivoting the movable contact member therein for operation by the

operating member to engage the stationary contact member in one position thereof upon movement of the operating member against its bias and to disengage the stationary contact member in the other position thereof upon movement of the operating member against its bias.

2. An electric switch having in combination, a stationary contact member, a movable contact member, a case having a biased operating member slidably mounted therein and provided with an aperture for extension of the movable contact member therethrough, and said case having means for reversely mounting the stationary contact member in two spaced-apart positions therein and means for reversely pivoting the movable contact member therein with the member extending through the aperture in the operating member for operation thereby to engage the stationary contact member in one position thereof upon movement of the operating member against its bias and to disengage the stationary contact member in the other position thereof upon movement of the operating member against its bias.

3. An electric switch having in combination, a stationary contact member having an integral terminal, a movable contact having a terminal flexibly connected therewith, a casing having a biased member slidably mounted therein and provided with slot means for reversely mounting said terminals in two spaced-apart positions and pivotal means for reversely pivoting the movable contact for operation by the biased member to engage the stationary contact member in one position of the integral terminal thereof upon movement of the biased member against its bias and to disengage the stationary contact member in the other position of the integral terminal thereof upon movement of the biased member against its bias.

4. An electric switch having in combination, a stationary contact member having a lateral contact facing at one end and a terminal at the other end, a movable contact member having a lateral contact facing and a terminal flexibly connected therewith, a case having an operating member slidably mounted therein and provided with biasing means and said case having slot means for reversely mounting the flexibly connected terminal and the stationary contact member in either of two spaced-apart positions with the terminal outside the case and with the lateral contact facing reversed inside the case and pivotal means for reversely pivoting the movable contact member inside the case for operation by the operating member to engage the lateral contact facing thereon with the lateral contact facing of the stationary contact member in one position thereof upon movement of the operating member against its bias and to disengage said contact facing in the other position of the stationary contact member upon movement of the operating member against its bias.
